PRESSURE-FLUID-ACTUATED MECHANISM.

1,332,845.

Specification of Letters Patent.

Patented Mar. 2, 1920.

Application filed April 2, 1917. Serial No. 159,167.

To all whom it may concern:

Be it known that I, WILLIAM H. KELLER, a citizen of the United States, residing at Fond du Lac, in the county of Fond du Lac and State of Wisconsin, have invented 5 certain new and useful Improvements in Pressure - Fluid - Actuated Mechanism, of which the following is a specification.

This invention relates broadly to pressure-fluid engines or motors of various 10 types and has particular reference to pneumatic or other pressure-fluid-actuated tools such as hammers, riveters, rock drills, tampers and the like. In such mechanisms there 15 is a reciprocatory valve which controls the flow of pressure fluid to and away from the cylinder or space in which the piston reciprocates. In many fluid-actuated tools, the piston or other reciprocatory member 20 makes in the neighborhood of two thousand reciprocations per minute, and the effectiveness and efficiency of the tool depends almost entirely upon the regularity and positiveness of these reciprocations.

25 Fluid-actuated tools of the reciprocatory-piston type may be divided into two classes, namely, those in which the piston travel extends to a point within the valve and those wherein the piston travel stops short of the 30 valve. In the first mentioned class of tools the proper operation of the valve has been interfered with through contact of the piston with the valve, and the valve has been subject to breakage on account of being 35 struck by the piston, particularly after the piston has become worn so as to have some side play in the piston chamber. In the other class of tools, the piston has been liable to strike the box or casing inclosing 40 the valve, the resulting jar producing jumping or fluttering of the valve and eventually causing crystallization of the metal and breakage of the parts.

The object of my invention, generally 45 stated, is to produce a pressure-fluid-actuated mechanism wherein maximum durability, effectiveness and strength are insured, and wherein the operation of the valve is rendered absolutely smooth and reliable and positively effective under varying 50 degrees of motive fluid pressure.

This object has been attained by locating 55 the valve within a valve casing or box comprising a sleeve or tubular guide upon the periphery of which the valve is slidable and

into which the piston travels in its reciprocations. Said sleeve or tubular guide thus keeps the valve and the piston out of contact with each other, thereby obviating the breakage and the irregularities of valve action which are so objectionable in tools of prior construction.

60 In the accompanying drawings, Figure 1 is a longitudinal central sectional view of a pneumatic tool embodying the features of my invention, the piston and valve being shown in the position occupied when the piston is in its rearward position and about to begin its forward stroke. Fig. 2 is a view similar to that of Fig. 1, but showing 65 the piston and the valve in the positions occupied after the piston has completed its forward stroke and has started on its return stroke. Fig. 3 is a fragmental view of the valve mechanism, upon an enlarged 70 scale.

The embodiment which has been selected to illustrate the invention comprises a cylinder or barrel 1, a sleeve 2 projecting forwardly from and integral with the cylinder 75 head or handle base 3, and a grasping handle 4. The cylinder 1 and the sleeve 2 may be connected in any suitable manner, as for example, by means of the screw threads 5. The piston is indicated at 6. 7 80 85 is a working tool associated in any suitable manner with the forward end of the cylinder 1.

The inlet passage 8 for the motive fluid extends through the handle 4 and is controlled in any suitable manner, as, for example, by means of a throttle valve operated by a thumb lever 9.

While the valve casing may be of any suitable construction, it is herein shown as 90 comprising a tubular body 10 and a cover or disk 11 arranged to fit against one end of the body 10. Integral with the cover 11 is a sleeve 12 extending axially of the body 10. The bore of the sleeve 12 is aligned 100 with and of the same diameter as the bore of the cylinder 1 and virtually constitutes the rear portion of the cylinder or piston chamber.

The tubular body 10 and the sleeve 12 105 are spaced apart so as to provide an annular chamber 13 to contain the valve 14. The latter is of annular or tubular construction and is adapted to slide in contact with the tubular body 10 and the sleeve 12, the tubu-

lar body and the sleeve therefore constituting guides for the valve.

The rear end of the cylinder 1 is placed in communication with the inlet passage 8 by means of ports 15 in the cylinder head 3, said ports communicating with a suitable number of ducts 16 in the tubular body 10 of the valve casing. The ducts 16 communicate with the rear end of the annular 10 valve chamber 13 in which the valve 14 reciprocates. The rear end of said chamber communicates with the rear end of the cylinder by means of ports 17. In its reciprocation the valve 14 opens and closes 15 communication between the ducts 16 and the ports 17.

Pressure fluid is admitted to the forward end of the cylinder 1 by means of passages 18 formed in the tubular body 10 of the 20 valve casing, said passages communicating at one end with the ports 15. The opposite ends of the passages 18 are closed by the valve 14 when the latter is in its forward position as shown in Fig. 1. The valve has 25 in its periphery an annular groove 19, which, when the valve is in its rearward position, communicates with the passages 18 and with a suitable number of ports 20 in the body 10. The ports 20 communicate 30 with passages 21 formed in the tubular body 10 and the cover 11. The passages 21 communicate with a suitable number of passages 22 extending to the forward end of the cylinder 1.

35 The motive fluid is exhausted from the space behind the piston through ports 23 formed in the sleeve 12. When the valve 14 is in its forward position as shown in Fig. 1, the exhaust ports 23 are covered by 40 the valve, but when said valve is in its rearward position as illustrated in Fig. 2, the exhaust ports 23 register with an annular groove 24 formed in the inner periphery of the valve. The groove 24 communicates 45 with a suitable number of ports 25 in the valve. When the latter is in its rearward position, the ports 25 register with an annular groove 26 formed in the inner wall of the tubular body 10. The groove 26 communicates 50 at all times through a suitable number of ports 27 with an annular space 28 surrounding the valve casing. The annular space 28 communicates at all times with the atmosphere through the ports 29.

55 By reference to Fig. 1, it will be seen that when the valve 14 is in its forward position motive fluid is free to escape from the space in front of the piston through the passages 21 and 22, the ports 20, the groove 19 in the valve 14, the groove 26 in the tubular body 9, the ports 27, the annular space 28 and the ports 29.

60 The valve 14 is reciprocated by means of fluid pressure exerted upon its opposite 35 ends. As will be evident from the draw-

ings, the rear end of the valve 14 is exposed at all times to fluid pressure through the ducts 16. The forward end of the valve is of larger area and is at times exposed to fluid pressure by means of a suitable number 70 of passages 30 communicating at their forward ends with the cylinder 1 at a point somewhat rearwardly of the position assumed by the piston at the end of its forward stroke. The rear ends of the passages 75 30 communicate with passages 31 in the cover 11, the passages 31 communicating with the forward end of the valve chamber 13 in which the valve 14 reciprocates.

32 is a passage communicating at its rear 80 end with one of the ports 15 and at its forward end with the forward end of the valve chamber 13. The passage 32 may be used to introduce a small amount of live motive fluid from the port 15 to the valve chamber 85 30 to assist in moving the valve if a quicker valve action is desired and the live motive fluid introduced into the valve chamber through the passages 30 and 31 after the passages 30 are uncovered by the piston on 90 its forward stroke is not considered sufficient in volume or pressure.

The operation of the mechanism is as follows:

When the parts are in the position shown 95 in Fig. 1, the motive fluid flows from the supply duct 8 in the handle, thence through the ports 15 and the ducts 16, and thence into the valve chamber 13. The motive fluid then passes from the chamber 13 100 through the ports 17 into the rear portion of the cylinder 1; and assuming that the piston 6 is in the position shown in Fig. 1, the piston will be driven forwardly into contact with the shank of the working tool 105 7. While the piston is traveling forward, the fluid in front of the piston flows through the passages 22, thence through the passages 21, through the ports 20 into the annular groove 19 of the valve 14, thence into the 110 groove 26 in the body 10 of the valve casing, thence through the ports 27 and into the annular space 28 and thence through the ports 29 to the atmosphere.

It will be noted that the ducts 16 of the 115 valve casing are always open to live motive fluid pressure and that live motive fluid can always pass freely through said ducts to the rear end of the valve chamber 13. It will also be seen that live motive fluid pressure is always being exerted through the ducts 16 and valve chamber 13 upon the rear end of the valve 14. However, when the piston 6 in its forward stroke has passed the forward end of the passages 30, live 125 motive fluid is permitted to flow through said passages and the passages 31 into the forward end of the valve chamber 13 where said fluid exerts pressure on the forward end of the valve 14; and as this end of the valve 130

is larger than the rear end, the valve will move rearwardly against the pressure of the live motive fluid which is being constantly exerted against the rear end of the valve.

5 The valve has now moved from the position shown in Fig. 1 to that illustrated in Fig. 2, thereby permitting live motive fluid to pass from the ports 15 through the passages 18 into the annular groove 19 in the valve, 10 through the ports 20 and through the passages 21 and 22 to the forward end of the cylinder, whereby the piston is caused to move from the position shown in Fig. 2 to the position shown in Fig. 1. While the 15 piston is traveling rearwardly, the fluid at the rear of the piston is exhausted to the atmosphere through the ports 23, the groove 24, the ports 25, the groove 26, the ports 27, the annular space 28 and the ports 29. In moving from the position 20 shown in Fig. 2 to that represented in Fig. 1, the piston has uncovered the forward end of the passages 30, thereby permitting the motive fluid to escape from the valve chamber 25 13 through the passages 30 and 31 into the cylinder, thus relieving the pressure on the forward end of the valve 14; and the constant pressure of motive fluid on the rear end of the valve has caused the valve 30 to move from the position shown in Fig. 2 to that illustrated in Fig. 1, thereby completing one cycle of operations.

It will be apparent that the valve 14 has a long bearing upon the tubular body 10 35 of the valve casing and the sleeve 12, and is thus effectively held against lateral or tilting movement, whereby efficiency and durability, with consequent economy in cost of maintenance, are obtained. Inasmuch as 40 the sleeve 12 is interposed between the piston and the valve, it is impossible for the piston and the valve to come into contact with each other or for any jar or vibration to be transmitted to the valve, and hence 45 the regularity and positiveness of the valve action cannot be affected by the piston. The jumping or fluttering of the valve as well as the breakage which have heretofore been such objectionable features in fluid-actuated 50 tools, are obviated.

Since the piston travels to a point within the valve casing, the cylinder 1 may be made shorter than would otherwise be possible,—a feature of particular importance 55 when the tool is to be used in restricted spaces. It will be understood that if further shortening of the stroke were desirable, the piston could be provided with the usual annular peripheral groove to open the forward 60 end of the passages 30.

The air trapped in the rear end of the piston chamber after the piston has closed the ports 17 effectively cushions the return stroke of the piston.

65 While I have described the present em-

bodiment of the invention with considerable particularity, it will be understood that the invention is not limited to the construction and arrangement of parts herein shown, and that the valve mechanism herein illustrated may be employed in various types of pressure-fluid-actuated apparatus.

I believe that I am the first to make a pneumatic or other fluid-actuated tool, the valve construction of which is such that the valve cannot possibly be affected in any way whatever as regards the regularity and positiveness of the valve action.

I claim as my invention:

1. A pressure-fluid-actuated mechanism 80 having, in combination, a cylinder; a handle having a forwardly extended tubular portion of substantial length, the forward end of which is secured on the rear end of the cylinder and the rear end of which has a closing wall so as to form a housing rearwardly of the cylinder; a piston in said cylinder; and valve mechanism in said housing for controlling the movements of the piston, said mechanism comprising a tubular sleeve between the cylinder and said wall of the handle and alined with the cylinder, a cylindrical body surrounding said sleeve and spaced therefrom to form with the wall of the handle a valve chamber; and a valve 85 member completely inclosed in said chamber and guided upon its opposite sides by said sleeve and body.

2. A pressure-fluid-actuated mechanism having, in combination, a cylinder; a handle 100 having a forwardly extended tubular portion of substantial length, the forward end of which is secured on the rear end of the cylinder and the rear end of which has a closing wall so as to form a housing rearwardly of the cylinder; a piston in said cylinder; and valve mechanism in said housing for controlling the movements of the piston, said mechanism comprising a tubular sleeve 105 between the cylinder and said wall of the handle and alined with the cylinder, a cylindrical body surrounding said sleeve and spaced therefrom to form with the wall of the handle a valve chamber, and a valve member completely inclosed in said chamber 110 and guided upon its opposite sides by said sleeve and body, said cylindrical body being made of such size relative to the tubular portion of the handle as to form an annular space between them.

3. A pressure-fluid-actuated mechanism having, in combination, a cylinder; a sleeve abutting the rear end of the cylinder in alinement therewith; a handle having a tubular portion of substantial length secured at its 125 forward end on the rear end of the cylinder and closed at its rear end so as to form a cover for the rear end of the sleeve against which it abuts, said sleeve having a series of radial inlet ports in its rear end and said 130

- handle having a pressure fluid supply passage and an inlet port leading forwardly from said passage; a tubular body surrounding said sleeve and spaced therefrom to form a valve chamber, said body having a duct in its rear end communicating with the port in the handle and opening into said valve chamber; and a tubular valve member completely inclosed within said chamber and 10 guided on its opposite sides by said sleeve and body to control said radial ports in the sleeve.
4. A pressure-fluid-actuated mechanism having, in combination, a cylinder; a piston 15 in said cylinder; and valve mechanism for controlling the movements of said piston

comprising a valve member and a valve casing at the rear end of the cylinder wholly inclosing said valve member, means for constantly admitting pressure fluid to the rear 20 end of said valve member, means for constantly admitting pressure fluid to the forward end of said valve member, the last mentioned means being arranged to admit a relatively restricted supply of pressure fluid 25 only, and piston controlled means for admitting a further supply of pressure fluid to the forward end of said valve member.

In testimony whereof I have hereunto set my hand.

WILLIAM H. KELLER.
